UNITED STATES PATENT OFFICE.

STEPHEN G. SZOPKO, OF NEW YORK, N. Y.

DESIGN FOR A TOY MONKEY.

51,309.

Specification for Design.

Patented Sept. 25, 1917.

Application filed March 28, 1917. Serial No. 158,136. Term of patent 3½ years.

To all whom it may concern:

Be it known that I, STEPHEN G. SZOPKO, a citizen of Hungary, and a resident of the city of New York, borough of Manhattan, in the county and State of New York, have invented a new, original, and ornamental Design for a Toy Monkey, of which the following is a specification, reference being had to the accompanying drawing, forming part thereof, and showing a perspective view of a toy monkey in a sitting position, illustrating my new design.

I claim:

The ornamental design for a toy monkey, as shown.

STEPHEN G. SZOPKO.
